COLLAPSIBLE AUXILIARY GUNSTOCK

Filed July 10, 1945

INVENTOR.

H. Gordon Howard

UNITED STATES PATENT OFFICE

2,441,487

COLLAPSIBLE AUXILIARY GUNSTOCK

Herman Gordon Howard, Denver, Colo.

Application July 10, 1945, Serial No. 604,172

4 Claims. (Cl. 42—72)

1

My invention relates to an adjustable attachment mechanism for supporting, steadyng and bracing a gun while sighting and firing.

An important object of the invention is to provide an adjustable attachment mechanism to the lateral face of the gunstock of firearms which is conveniently adjustable to the shoulder opposite the shoulder from the one on which the gun-butt of the gunstock rests, and which is so adjustable as to steady, support and brace the gun while sighting, in consequence whereof the accuracy of gunfire is steadied and defined.

Another object of the invention is to provide an adjustable attachment mechanism to either lateral face of the gunstock of firearms, which acts as an additional shoulder-rest, and thereby improve steadiness in holding the firearm, and as a direct result thereof the accuracy of gunfire is increased.

A further important object of the invention is to provide an adjustable attachment mechanism to the gunstock of firearms which will operate as an additional absorbent of any kickback force of the gun during firing thereof.

A search of the official Patent Gazettes of the Patent Office of the United States indicates that there has been, prior to my invention, no history of prior art along this line of invention. Therefore, I assume that my invention is not an improvement of any prior invention or discovery, but is on the other hand, an entirely new invention.

Some improvements were made in the past in butts of gunstock and in gunstock curvature, and in one invention a gunstock itself was placed on a swinging adjustment, and in another case a removable gunstock for pistols was patented, but in no case has a separate adjustable attachment mechanism for supporting, steadyng and bracing a gun while sighting and firing been invented or discovered prior to my invention thereof.

I attain the objects heretofore set forth herein by the mechanism illustrated in the accompanying drawings, in which for the purpose of illustration, is shown a preferred embodiment of my invention.

Similar numerals refer to similar parts throughout the several views.

Figure 1 is a perspective view of the adjustable attachment mechanism embodying my invention, with the said attachment mechanism folded into the lateral face of the gunstock,

Figure 2 is a perspective view of the adjustable attachment mechanism embodying my in-

2

vention, with the said attachment mechanism in position for operation,

Figure 3 is a section view taken on line 3—3 of Figure 1, of the adjustable attachment mechanism,

Figure 4 is a section view of a part of the machine or mechanism taken on line 4—4 of Figure 3,

Figure 5 is a section view of a part of the said mechanism or apparatus taken on line 5—5 of Figure 3.

The entire framework of the adjustable attachment mechanism fits nearly flush into a channel or T-shaped slot 9 in the lateral face of the gunstock until ready for use, as shown in Figure 1 of the drawings which accompany this specification.

The main arm member 10, the extension arm member 11 having a shoulder rest affixed thereto, 20 the pivot or hinge pin 12, the U-shaped member 13, the adjustable set screw, with a handle 14, and the wing nut thumbscrew 15, constitute the principal parts of the adjustable attachment mechanism for auxiliary gunstocks, which may 25 be made of metal or other suitable substance.

The numeral 10 designates the main arm member which is engaged at the forward portion of the gunstock by the pivot pin 12, which is permanently set into the gunstock in a vertical 30 position and which projects through and secures the main arm member 10 and the U-shaped member 13 to the gunstock. The movement of the main arm member 10 is independent of the pin 12 as well as the U-shaped member 13.

The main arm member 10 has a channeled 35 groove 16 therein, and the extension arm member 11 which is preferably also channeled is slidably mounted therein. The main arm member 10 and the extension arm member 11 have an 40 elongated slot 17 therein which is contiguous or in juxtaposition to both of said arm members and through which the wing nut thumbscrew 15 projects. The slidable movement of the extension arm member 11 in the main arm member 10 is 45 independent of the wing nut thumbscrew 15 which is engaged by a bolt 18, and said wing nut thumbscrew is employed to bind fast the extension arm member 11 to the main arm member 10 at any point of elongation along the slidable axis 50 of the extension arm member 11 in coincidence with the main arm member 10, as the relative relation of the said arm members bear to the elongated slot 17 hereinbefore described.

The U-shaped member 13 is further engaged 55 to the gunstock preferably by means of nuts

19 which are screwed onto the threaded ends of the projecting forked arms of the U-shaped member which projecting furcated arms are imbedded in the wood of the gunstock.

The pivot pin 12 and the U-shaped member 13 are immobile and are independent of each other, and the main arm member 10 together with its extension arm member 11 rotate about the vertical axis of the pivot pin 12 and the head of the U-shaped member 13 as the adjustable attachment mechanism is swung outwardly and away from the gunstock for adjustment to the opposite shoulder from the shoulder on which the gunbutt of the gunstock rests.

The adjustable set screw 14 having a handle affixed thereto is employed to clamp tight the adjustable attachment mechanism at any angle that is made between the gunstock and the adjustable attachment mechanism in effecting a proper adjustment of the said attachment mechanism for use while sighting and firing the gun.

The adjustable set screw 14 projects through the head of the main arm member 10 and engages the main arm member 10 with the U-shaped member 13.

A thumb notch 21 is made in the slot in the lateral face of the gunstock directly above the handle on the set screw 14 to allow loosening of the set screw in preparation for swinging the said attachment mechanism into position for use.

A thumb notch 22 is made at the head of the slot in the lateral face of the gunstock directly behind the shoulder-rest portion 24 of the arm 11 of the auxiliary stock, which thumb-notch permits thumbnail access to depression 20 in the butt of the said shoulder-rest 24 thereby permitting the attachment mechanism to be quickly pulled away from the gunstock for adjustment.

It is understood that the form of my invention, herewith shown and described, is to be taken as a preferred example of the same, and that various changes in the shape, size, and arrangement of parts may be resorted to, without departing from the spirit of my invention, or the scope of the subjoined claims.

The operation of the collapsible auxiliary gunstock is as follows: When not in use the entire framework of the said collapsible auxiliary gunstock fits nearly flush into a slot 9, in the lateral face of the main gunstock 23, as shown in Figure 1 of the drawings. In using the collapsible auxiliary gunstock, the gunner inserts his thumb into the thumb-notch 21 and loosens the set screw 14 having a handle affixed thereto, by pulling the handle attached to the set screw away from the gunstock. The gunner then inserts his thumb into thumb notch 22 and into thumb-like depression 20 in the butt of the said shoulder rest of the collapsible auxiliary gunstock, and pulls the

said mechanism away from the gunstock 23 for adjustment to the shoulder opposite to the shoulder on which the gunbutt of the main gunstock 23 rests, while the said gunner is sighting and firing the gun. The gunner then adjusts the shoulder rest of the collapsible auxiliary gunstock to the shoulder which is opposite the shoulder on which the gunbutt of the main gunstock 23 rests, and clamps the adjustable set screw 14 tight, in order that the said mechanism will remain in proper adjustment, as an auxiliary shoulder rest while sighting and firing the gun. The gunner may, if desired, change the length of the said collapsible auxiliary gunstock mechanism, in making an adjustment thereof to his shoulder as hereinbefore described, by loosening the thumbscrew 15 and sliding the extension arm member 11 in the channeled groove 16 of the main arm member 10, and then by tightening the said thumbscrew 15 when the desired adjustment for length has been attained.

Having thus described my invention, I claim:

1. In combination a gun stock having a longitudinally extending recess in its side, and an auxiliary stock having one end pivotally mounted in the forward end of said recess, said auxiliary stock being constructed and arranged to swing on said pivot mounting laterally of said main stock and being adapted to swing into said recess.
2. In a structure as defined in claim 1, said auxiliary stock being telescopically extensible and collapsible whereby it may be selectively collapsed to fit into said recess and extended when swung out of said recess.
3. In a structure as defined in claim 1, said auxiliary stock having a butt member and said recess being substantially T-shaped with the cross of the T at the rear end of the recess to accommodate said butt member.
4. In a structure as defined in claim 1, said pivotally mounted end having means for locking the hinged parts in fixed interrelative angularity.

H. GORDON HOWARD.
